UNITED STATES PATENT OFFICE

148,092

DESIGN FOR A WALL CABINET UNIT

René Rouillard, Landrienne, Quebec, Canada

Application June 21, 1946, Serial No. 130,923

Term of patent 3½ years

(Cl. D33—19)

To all whom it may concern:

Be it known that I, René Rouillard, subject of the King of Great Britain, residing at Landrienne, county of Abitibi, Province of Quebec, Dominion of Canada, have invented a new, original, and ornamental Design for Wall Cabinet Unit, of which the following is a specification, reference being had to the accompanying drawing, forming part thereof.

Figure 1 of the drawing is a perspective view showing my new design.

Figure 2 is a sectional view taken on line 2—2 of Figure 1.

I claim:

The ornamental design for wall cabinet unit, as shown.

RENÉ ROUILLARD.
